UNITED STATES PATENT OFFICE.

FRIEND FOWLER, OF MOOSE JAW, SASKATCHEWAN, CANADA.

GRAIN CLEANER.

1,426,270.

Specification of Letters Patent. Patented Aug. 15, 1922.

Application filed April 20, 1920. Serial No. 375,300.

To all whom it may concern:

Be it known that I, FRIEND FOWLER, a citizen of Canada, and a resident of Moose Jaw, in the Province of Saskatchewan and 5 Dominion of Canada, have invented a new and Improved Grain Cleaner, of which the following is a full, clear, and exact description.

This invention relates to a grain cleaner, 10 and aims more particularly to provide a device of this nature which may be attached to a conventional threshing machine, and by means of which the chaff will be separated from the grains, these grains in turn 15 being sub-divided into a lighter and heavier grade, and the dust separated from this latter.

A further object of my invention is the construction of a grain separator which 20 shall be provided with a separating apparatus permitting this sub-division, which separating apparatus shall be operated by means of extremely simple mechanism and shall embody a simplified and efficient construction permitting of a quick separation 25 of the various particles.

Reference is had to the attached sheet of drawings which illustrate practical embodiments of my invention, and in which drawings,

Figure 1 is a side view of a grain separator constructed in accordance with my invention.

Figure 2 is a plan view thereof.

Figure 3 is a partly sectional side view.

Figure 4 illustrates a portion of the apparatus in section such view being a plan view.

Figures 5, 6, 7, 8, 9 and 10 are partly 40 section enlarged views showing details of the construction whereby my objects are accomplished, and

Figures 11, 12 and 13 show a slightly modified form of operating mechanism 45 which may be preferably employed to cause a separation of the various particles of the mixture.

In all these views like reference numerals 50 designate similar parts, and the reference numeral 15 indicates a threshing machine provided with a conventional spout pipe 16 housing an endless conveyor which may be operated by any suitable mechanism, such as a chain and gear wheel drive 17, and 55 which conveyor serves to bring the mixture to be separated to a point upon the trough

18 into which the same is deposited by means of said endless conveyor.

A drive for the apparatus providing a separation is provided in the construction 60 illustrated in Figures 1 to 10, which drive conveniently includes a crank shaft 19 rotating in suitable bearings 20 within an inclined chute 21, and this crank shaft may be moved by any suitable form of drive 65 such as an extensible shaft 22 permitting of adjustment, one end of such shaft being connected by any suitable form of universal joint 23 to the crank shaft 19, the opposite end of said shaft 22 being conveniently 70 driven by a train of beveled gears 24, which may derive their power from the drive 17.

The chute 21 is sub-divided adjacent its lower end into preferably four smaller chutes or tubes, 25, 26, 27 and 28 respectively, the upper end of the chutes being formed with an inclined baffle 29 positioned over the crank shaft 19. It will now be understood that the mass to be separated is free from the spout pipe 16 by means of 80 the endless conveyor into the trough 18 through which it falls on to the baffle 29, and from this baffle it passes on to an apron such as 30. Subsequent to its passage over the apron 30 it passes through the separating mechanism operated by means of the crank shaft 19 and passes into the smaller chutes or tubes 25, 26, 27 and 28 in the form of chaff, heavier grain, lighter grain and 85 dust in the order named, it being understood that any suitable means for producing suction is connected with these smaller tubes or chutes to draw the particles deposited within the upper ends of the same 90 into suitable receiving vats it being further appreciated that the blower 30' may conveniently be secured to the conveyor 16, which blower may introduce a blast of air within the chute by means of a flexible pipe such as 30''. By this provision it will be understood that a nozzle 30''' may be arranged 95 in the chute, serving to facilitate the action of the machine.

The sorting mechanism conveniently includes a primary screen 31 formed with comparatively large interstices of such size as to permit the passage of the grain kernels, but preventing the chaff from passing through the meshes of the same. A second screen 32 is positioned below the first named screen, 110 the openings in this latter screen being slightly smaller to prevent the passage there-

through of small grain and dust, larger grain passing through the screen into the chute 26. The smaller grain and dust passes as aforestated through the screen 32 and 5 onto the screen 33 which is formed with such a small mesh as to prevent the passage of the smallest of grains which are retained by the same, and dust into the chute 27, the dust passing finally through the screen 33 10 and thence into the chute 28.

Obviously a suitable means must be provided for moving the screens, and with this in view I provide connecting rods 34, which extend between the crank shaft 19 and the 15 forward end of a yoke, such as 34', which has its rear ends connected to one of the screens so that upon a rotation of the crank shaft the screens will be reciprocated. With a view of providing means which will permit 20 of a moving of the screens in the manner required with a minimum of friction, the chute 21 is provided with transversely extending bars mounting rollers 36 which bars and rollers extend below the screens. Carriages are provided for each of the screens 25 which carriages conveniently include longitudinally extending angle irons 37 the lower edges of which bear against the rollers 36, and it will be appreciated that by this construction the screens may be moved with the utmost ease.

Positioned below each of the screens is a member forming a combing device 38 which co-operates with the under-face of the screen 35 to facilitate the passage of any particles which might have become wedged within the meshes of the same, this member being held in position by any suitable means such as arms 39 extending beyond the ends of the 40 combing device and secured in applied position by transversely extending rods 40 passing through the walls of the chute 21. It is to be noted in this connection that the 45 said combing may take any convenient form, but I preferably utilize an element of this nature including a body portion 38 formed with an opening, the body being bent upwardly adjacent the openings thus formed to provide toothed portions 38' which terminate adjacent the lower face of the screens 50 32 to perform the functions stated. The combing device may however be separated so that its upper edges are always closely spaced from the under-face of the screen by 55 means of rollers such as 41 which rest upon the upper face of the angle iron 37, so that a minimum friction is encountered. The carriages formed by the angle irons are further preferably provided adjacent their 60 longitudinal upper edges with a deflector 42 which serves to prevent particles from lodging between the outer edges of the carriages and inner face of the chute, and thus prevents a clogging of the entire machine. The 65 lowermost of the screen carriages con-

veniently carries a trough shaped receptacle 43 so that the dust passing through the lowermost of the screens may be agitated to a sufficient extent to permit the suction to take hold of the same and to conduct it into 70 the tube 28.

The operating mechanism aforescribed may be dispensed with and the mechanism shown in Figures 11, 12 and 13 may be substituted in lieu thereof, to advantage, 75 and it will be noted that this mechanism conveniently includes a crank arm 44 mounted upon the spout pipe 16, and be driven by any suitable means, which crank arm will reciprocate a rod 45 having secured adjacent its upper end a pair of links 46 and 47 respectively, the former having in turn secured to its outer end, a lever 48 formed with slots 49 adjacent its outer end into which slots pins 50 connected to the links project. The link 47 is also formed with a slot adjacent its upper end, and the pin 50 of the intermediate screen 32 may be conveniently connected to this link by the means described. 85

It will be appreciated that in operation, this latter device causes a retraction of the uppermost screen simultaneously with the projection of the lowermost of the screens and the retraction of the intermediate screen. 95

Obviously, numerous modifications of this structure described might be resorted to without in the least departing from the scope of my claims.

Having thus described my invention, what 100 I claim as new and desire to secure by Letters Patent is as follows:—

1. A grain separator including a chute, a plurality of carriages disposed within said chute and arranged one above the other, 105 means extending within said chute for movably supporting each of said carriages, means connected to said carriages for reciprocating the same, each of said carriages including side members co-operating with said supporting means, a screen extending between said side members, and deflectors carried by the side members of each of said carriages, the deflectors of each carriage extending upwardly and inwardly therefrom 110 and terminating at a point short of the supporting means of the next higher carriage. 115

2. A grain separator including a chute, supporting means positioned within said chute, carriages movably resting upon said 120 supporting means, said carriages each comprising angle irons and screens extending between said angle irons, a combing device arranged below each of said screens, supporting means interposed between said 125 combing device and the upper face of the lowermost arm of each of said angle irons, and means for reciprocating each of said carriages.

3. A grain separator including a chute, 130

supporting means positioned within said chute, carriages movably resting upon said supporting means, said carriages each comprising angle irons and screens extending between said angle irons, a combing device arranged below each of said screens, said screens being spaced from the upper face of the lowermost arm of each of said angle irons, the side edges of said combing device 5 extending into the space thus provided, supporting means interposed between the upper faces of the lowermost arms of each of said angle irons and said combing device, and means for reciprocating each of said carriages.

4. A grain separator including a chute, supporting means positioned within said

chute, carriages movably resting upon said supporting means, said carriages each comprising angle irons and screens extending between said angle irons, a combing device arranged below each of said screens, said screens being spaced from the upper face of the lowermost arm of each of said angle irons, the side edges of said combing device 20 extending into the space thus provided, rollers interposed between the upper faces of the lowermost arms of said angle irons and said combing device, means for retaining said combing device relatively fixed within 25 said chute, and means for reciprocating each of said carriages.

FRIEND FOWLER.
